ADJUSTABLE CHAIR

John C. Holten, St. Paul, Minn.

Application April 1, 1947, Serial No. 738,633

6 Claims. (Cl. 155—161)

1

My invention comprises a new and simplified seat and back supporting frame assembly for a chair having an adjustable back. Such chairs are well known, being generally used by office workers, particularly stenographers; but existing constructions which afford an equal degree of adjustability are unduly complicated and expensive to manufacture, and since they are constructed from a large number of separate parts, correspondingly are subject to derangement. My invention aims to simplify and lighten the seat frame and back adjustment assembly, and to reduce the cost of manufacture of chairs of this general type. With constantly increasing labor costs it becomes more and more necessary to reduce the hours of labor required to manufacture and assemble such chairs and my invention represents a substantial advance in this art. A further advantage of such simplified construction is that with fewer parts there is less opportunity for any of said parts to work out of adjustment and consequently fewer repairs are necessary and maintenance costs are lowered.

A preferred form of my invention is shown in the attached drawings, in which:

Figure 1 is a perspective view showing a complete chair embodying my novel seat and back assembly;

Figure 2 is a cross-sectional view taken along the line 2—2 of Figure 3, looking in the direction of the arrows; and

Figure 3 is a bottom plan view showing the spider and backframe tension and inclination adjustments.

Similar numerals refer to similar parts throughout the several views.

Referring to Figure 1, the invention is illustrated as embodied in a stenographer's chair having a cushion seat 5 and adjustable backrest 6 carried by ears 7 which are pivotally and slidably mounted in slots 8 in the bracket 9 on the back frame 11. This is accomplished by means of bolts passing through said ears 7 and slots 8, and capped by adjustable nuts 10. It will thus be seen that by loosening the nuts 10, the backrest may be adjusted to any angle and height desired, and then secured in this position by simply tightening the nuts 10. The chair base 12 is supported on legs 13, preferably provided with casters, and has a central vertical bore in which is mounted a standard 14, the height of which standard may be adjusted by means of the hand bolt 15, the inner end of which bears against the surface of said standard 14. At the top of the standard an integral four-armed spider 16 is provided in order

5 to support the seat 5, and the ends of the two rearwardly projecting arms of said spider are formed into generally U-shaped pivot receiving means 17 for supporting the back frame 11. The core of said spider 16 is extended downwardly, forming a hollow cylinder 18 within which the upper end of the standard 14 is rotatable, a steel ball 19 being interposed between the top of the standard and the closed upper end of the hollow cylinder. The standard 14 is rotatably secured in the hollow cylinder 18 of the seat frame by means of a set-screw 20, the point of which engages in a groove 21 in the standard 14 as shown in Figure 2.

15 The back frame is made of tubing in two parts, the upper part 11 being steel or aluminum, and the lower part 22 being steel, connected by steel plugs 23 which are drilled to receive the pivot pins 24 which secure the back frame in the U-shaped extremities 17 of the rear arms of the spider. The side limbs 25 of the lower part of the back frame 20 pass loosely between the branches of the U-shaped extremities 17 of the rear arms of the spider and are securely held for pivotal movement therein by the pivot pins 24. The bottom of the 25 back frame passes transversely through a sleeve fitting 26 at its middle point, in which it fits snugly but with sufficient clearance to permit it to turn slightly. This sleeve 26 is assembled on the frame tube 22 before the ends of the latter are bent to engage with the U-shaped pivot arms of the spider.

An adjusting screw 27, having a hand wheel 28 on its outer end, is threaded through a transverse bore in a lug on the upper side of the sleeve 26 for adjusting the inclination of the back frame. The inner end of this screw 27 is rotatably secured to the end of a yoke 29 surrounding the hollow stem 18 of the seat frame. In the form of the invention shown the screw 27 has its inner end journaled in alining holes in the yoke 29, which is formed with a double wall at one end by welding an outer plate 30 against its end, as shown in Figure 3. The adjusting screw has a square head 31 engaging between the plate 30 and the end of 45 the swivel 29 so that it may rotate freely, but is prevented from slipping out by the head 31.

Near the lower edge of said cylinder 18 and in axial alinement with the adjusting screw 27, a horizontal threaded aperture is provided extending through the front wall of the cylinder, the outer edge of said aperture being surrounded by a raised boss having a flat front surface, and this aperture fixedly supports a pin 32, threaded at each end. The pin 32 passes through a registering aperture 33 in the front end of the yoke

29 and is encircled by a helical spring 34 which is retained by an adjusting nut 35 having a forwardly projecting handle 36 by means of which said nut may be readily turned to adjust the tension of said spring.

From this it will be seen that by rotating the adjusting screw 27 by means of its handle 28 the sleeve member 26 may be moved forward or back and the back of the chair, pivoting about the pins 24, may be inclined at any desired angle relative to the seat, the spring 34 normally retaining the swivel rearwardly against the boss on the front surface of the cylinder 18, but permitting forward movement of the yoke 29 when pressure is exerted against the back frame of the chair. Thus, when the occupant of the chair leans against the back, its frame will pivot about the pins 24 and the forward part of the swivel 29 will be forced forward against the pressure of the helical spring 34. It will be seen that the amount of "give" in the back may be regulated by varying the pressure exerted on the front of the helical spring 34 by loosening or tightening the nut 35, which may readily be done by the occupant of the chair by turning the handle 36 one way or the other.

By means of this construction I eliminate the necessity of assembling the seat frame from a number of different parts, simplify the construction of the tension adjustment for the back, and combine in one assembly both tension and inclination adjustments which have hitherto necessitated two separate sub-assemblies.

What I claim is:

1. In a chair, a supporting standard, a seat frame mounted thereon, a backrest pivotally connected to said seat frame, a spindle attached at one end to said seat frame and extending forwardly therefrom, a yoke member surrounding said standard and slidably mounted at its front end on said spindle, a horizontal member rotatably mounted on said back rest near its lower extremity, a longitudinal member adjustably and rotatably mounted near one end in said horizontal member and rotatably mounted at its other end in the back end of said yoke, spring means surrounding a portion of said spindle, and an adjustable nut mounted near the end of said spindle.

2. In a chair having a seat frame comprising a supporting base, a backrest pivotally connected to said seat frame, a spindle projecting forwardly from the base of said seat frame, a yoke member encircling said base near its upper end and connected through pivot means to said backrest, said yoke member being slidably mounted on said spindle, and adjustable stop means yieldably restraining forward movement of said yoke member upon said spindle.

3. A chair seat and back assembly comprising a supporting standard and seat frame, a backrest pivotally connected to said seat frame, a horizontal member rotatably mounted on said backrest and a longitudinal member embracing said standard and connected through spring means to said seat frame at one end and carrying at its other end an adjusting screw rotatably and adjustably mounted in said horizontal member at the other end.

4. A chair seat and back assembly as described in claim 3 wherein the seat frame is a unitary member provided with integral pivot supports adjacent the rear corners of the seat.

5. In a chair, a supporting standard, a seat frame mounted thereon, a backrest pivotally connected to said seat frame, a horizontal member rotatably mounted on said backrest and a longitudinal member connected through yoke means to said seat frame at one end and adjustably and rotatably mounted in said horizontal member near its other end.

6. In a chair having a supporting assembly comprising a seat frame, a base, and a standard mounted on said base and supporting said seat frame, a back rest pivotally connected at spaced points above its lower extremity to said supporting assembly, a spindle attached at one end to said supporting assembly and extending forwardly therefrom, a yoke encircling said standard and slidably mounted at its front end on said spindle, a horizontal member rotatably mounted on said back rest near its lower extremity, a longitudinal member adjustably and rotatably mounted near one end in and transversely of said horizontal member and rotatably mounted at its other end in the back end of said yoke, spring means encircling said spindle and bearing against the forward end of said yoke member, and an adjustable nut mounted near the end of said spindle for maintaining said spring means under tension.

JOHN C. HOLTEN.
